WAVE TRANSLATOR

Donald D. Grieg, Forest Hills, N. Y., assignor to
 Federal Telephone and Radio Corporation,
 Newark, N. J., a corporation of Delaware

Application April 30, 1943, Serial No. 485,104

14 Claims. (Cl. 250—27)

1

This invention relates to radio receivers.

In my copending application Serial No. 459,959, filed September 28, 1942, I disclose a demodulator for time modulated pulses. By time modulated pulses I have reference to that form of pulse modulation where the pulses are time displaced from given recurrence timing according to the instantaneous amplitude of an intelligence signal wave. This time displacement may take any one of several forms, one of which is known as "push-pull" time modulation by which the successive pulses are displaced toward and away from each other in push-pull manner. Regardless of the manner of time displacement, the demodulator of my aforesaid application translates the displacement of the time modulated pulses into pulses, the amplitudes of which correspond to the time displacements of the time modulated pulses.

One of the objects of my invention is to provide a radio receiver adapted to detect and translate amplitude modulated signals into equivalent time modulated signals for demodulation in a T. M. (time modulation) demodulator such, for example, as disclosed in my aforesaid copending application.

Another object of my invention is to provide a method and means for translating an amplitude modulated carrier wave into an equivalent train of time modulated impulses; and further, wherein the translation operation is such as to substantially eliminate or at least greatly reduce noise and other interfering voltage fluctuations occurring on the received carrier.

According to my invention, an amplitude modulated carrier wave is detected in the usual manner and is then translated into an equivalent train of time modulated impulses by first limit clipping the modulated carrier between two limits selected where the sides of the undulations of the carrier wave vary in slope in substantially linear proportion to the amplitude variations of the corresponding undulations. This produces a trapezoidal wave the side edges of each cycle of which slope in proportion substantially to the amplitude of the corresponding undulations of the carrier. This trapezoidal wave is then differentiated to produce alternate positive and negative rectangular pulses one each for each cycle of the trapezoidal wave. The width of each of these rectangular pulses corresponds to the slope of the corresponding edge of the trapezoidal wave and therefore corresponds also with the amplitude of the corresponding undulation of the carrier wave. The amplitude of the rectangular pulses are also

2

varied according to variations in the slope of the corresponding edges of the trapezoidal wave from which they are produced. It is sometimes preferable to limit the rectangular pulses to the same amplitude. This may be done by passing the train of rectangular pulses through a limiting device such as a gate clipper. By thereafter differentiating the rectangular pulses, a pair of positive and negative impulses is produced for each rectangular pulse, one of the impulses of each pair corresponding to the leading edge and the other corresponding to the trailing edge of one of the rectangular pulses. It follows, therefore, that these impulses are time displaced in accordance with the width of the corresponding rectangular pulses and this displacement corresponds with variation in amplitude of the corresponding undulation of the carrier wave.

The train of rectangular pulses produced from the trapezoidal wave may be directly differentiated without being limited to the same amplitude. By differentiating these rectangular pulses, which not only vary in width but also in amplitude, pairs of narrow width impulses will be produced, the impulses of each pair being displaced according to the width of the rectangular pulse from which they are produced. These impulses will also vary in amplitude in accordance with the amplitude of the rectangular pulse from which they are formed. Before applying this train of impulses to a T. M. demodulator, it will be desirable first to limit clip the impulses to the same amplitude. This may be accomplished by either gate clipping the positive or negative pulses or by including both between the clipping limits whichever may be desired.

One of the advantages obtained by this conversion process is that the limit clipping operation of slicing a small portion from the carrier wave near the axis thereof, eliminates substantially all noise and other interfering voltage fluctuations present on the carrier wave without adversely affecting the modulating intelligence. Thus, by translation, an improvement in the signal-to-noise ratio is obtained over the usual amplitude demodulation methods.

For a further understanding of the invention, reference may be had to the following detailed description to be read in connection with the accompanying drawings, in which:

Fig. 1 is a block diagram of a radio receiver according to my invention;

Fig. 2 is a graphical representation of an amplitude modulated carrier wave; and

Fig. 3 is a graphical illustration of a part of the

carrier greatly enlarged together with additional curves illustrating the translation operations in accordance with my invention.

Referring to Fig. 1, a radio receiver is shown provided with a radio frequency stage 10 connected to a receiving antenna 12. The radio frequency stage is connected to an intermediate frequency stage or stages 13. The wave translating feature of the receiver includes a first gate clipper 14, a first differentiator 15, a second gate clipper 16 and a second differentiator 17. The output of the second differentiator, which comprises a train of time modulated impulses corresponding in time displacement to variations in amplitude of the input amplitude modulated wave, is applied to a T. M. demodulator 18 for demodulation of the time modulated impulses. While the demodulator 18 may be of various constructions it preferably is of the character disclosed in my aforesaid copending application Serial No. 459,959. This demodulation, for example, preferably is of the character involving the generating or synchronizing of an energy wave having recurring inclined portions, the period of which is comparable to the time spacing of the impulses. The wave and the impulses are combined, the impulses being superimposed on the wave at points along the inclined portions thereof according to the time displacement of the impulses. This produces output pulse energy which varies in amplitude according to the time modulation of the input impulses.

The gate clippers 14 and 16 are preferably of the character arranged to limit clip between two predetermined limits. A gate clipper of this character is disclosed in a copending application of E. Labin and myself Serial No. 437,530, filed April 3, 1942. The gate clipper therein disclosed includes a diode-double-limiter tube having two limiting levels whereby a wave applied thereto is limited to the breadth determined by those limiting levels. This double limiting operation produces a trapezoidal wave form when an amplitude modulated carrier wave such as the wave 20 of Fig. 2 is applied to the gate clipper 14. Should the gate clipper have a narrow band-pass characteristic, the intermediate frequency at the stage 13 is preferably "beat down" to a low intermediate frequency before it is applied to the clipper 14. This low intermediate frequency insures well-defined corners for the trapezoidal wave. Should a gate clipper be chosen having wide band-pass characteristics, the low intermediate frequency stage or the "beating down" of high intermediate frequency may then be omitted.

Referring particularly to Fig. 3 in which the curves thereof are applied to the same time base, curve *a* shows an enlarged portion of the amplitude modulated wave 20 clipped between limits 24 and 25. While I have shown these limiting levels to be equally spaced on opposite sides of the axis of the carrier wave, it will be understood that they may be selected to one side or the other of the axis if desired. The importance of this selection is that the sides of the undulations between the limiting levels should be such that the slopes thereof vary in substantially linear proportion to the amplitude variation of the corresponding undulations. It is preferable, therefore, that the limit clipping operation be made near the axis of the carrier.

It will also be noted that in limit clipping the carrier wave 20 at the axis thereof that a large portion of the undulations 21, 22, 23 etc. forming the envelopes of the wave are eliminated. The portion of the wave obtained by this operation

comprises a trapezoidal wave 30 the sides of which are the only portions of the outer surfaces of the undulations of the wave that are retained. Accordingly, the time interval covered by the sides 5 of the trapezoidal wave comprises a very small percentage of the period of the carrier. For example, this reduction may amount to as great as 100 to 1 or greater depending, of course, on the breadth of the limits 24, 25. This elimination of 10 such a large percentage of the undulations eliminates to a very large extent such noise and other interfering voltage fluctuations as indicated by the broken lines 27 and 28. The feature of reducing noise and other interfering voltage fluctuations 15 in amplitude modulated carrier waves is the subject matter of my copending application Serial No. 483,866, filed April 16, 1943, wherein a very large percentage of interference is eliminated by an operation translating the amplitude modulated wave into a train of pulses which is correspondingly modulated in amplitude.

The sides of the cycles 31, 32, 33 etc. of the trapezoidal wave 30 vary in slope from cycle to cycle in proportion to the amplitude variations 25 of the corresponding undulations 21, 22, 23 etc. If the gate opening of the clipper 14 is small compared to the mean amplitude of the carrier, the change in slope of the side edges of the cycles 30 will be a linear function of the initial modulation of the carrier.

The first differentiator 15 operates to translate the trapezoidal wave 30 into rectangular pulses 31*a*, 31*b*, 32*a*, 32*b*; etc. as shown by curve *b*. These rectangular pulses not only correspond in 35 width to the slope of the corresponding side edges of the cycles of the trapezoidal waves but also vary proportionately in amplitude to the steepness of the sloping side edges. The rectangular pulses of curve *b* shown in solid line represent 40 the output of the second gate clipper 16 after the pulses from the differentiator 15 have been limit clipped between the levels 34 and 35. The portions of the rectangular pulses clipped away by this operation are indicated in broken lines. 45 This produces a train of pulses in which the pulses are of the same amplitude.

The rectangular pulses of curve *b* are differentiated by the second differentiator 17 to produce 50 pairs of positive and negative impulses shown by curve *c*. The impulses of each pair, such as impulses 31*ap* and 31*an*, are displaced according to the width of the corresponding rectangular pulse. These pulses of curve *c* may be applied directly to the demodulator 18 for demodulation 55 in accordance with the disclosure in my aforesaid copending application Serial No. 459,959. By reference to this copending application, it will be seen that the positive pulses 31*ap*, 31*bp*, 32*ap* etc. will be used for purposes of demodulation. 60 If it is desired to use the negative pulses 31*an*, 31*bn* etc., a further clipping operation will be necessary. Such a clipping operation is indicated by the limit levels 44 and 45. Such a clipping operation will produce a train of pulses according to curve *d*.

The displacement of the pulses of curve *d* depends upon the width of the rectangular pulses of curve *b* which in turn depend for their width upon the steepness of the sides of the cycles of 70 the trapezoidal wave 30. It will thus be observed that the time displacement of the impulses of curves *c* and *d* correspond with the variations in amplitude of the corresponding undulations of the carrier wave 20.

In regard to the clipping operation of the sec-

ond gate clipper 16, it will be recognized that the clipping operation need not be selected between the limits 34 and 35. In other words, the limits may be to one side of the axis of the curve so as to obtain at that point in the system unidirectional rectangular pulses. Differentiation of such unidirectional pulses will produce the corresponding impulses of curve c.

It will be further recognized that the second gate clipper 16 and the second differentiator 17 of Fig. 1 may be interchanged so that the rectangular pulses of curve b as indicated in broken lines are first differentiated before a clipping operation is performed. Such interchanging of the two stages 16 and 17 will produce impulses for curve c which vary in amplitude proportionately with the amplitude of the pulses (broken lines) of curve b. By limit clipping such a train of impulses by limits 44 and 45, for example, a train of unidirectional impulses will be produced similarly as indicated by curve d containing time modulation according to the amplitude modulation of the carrier wave.

While I have shown and described the principles of my invention in connection with specific apparatus, it is to be understood that the illustrations thereof are given by way of example only and not as limiting the scope of the invention as set forth in the objects and the appended claims.

I claim:

1. A method of translating an amplitude modulated carrier wave into an equivalent train of time modulated impulses comprising translating the undulations of the amplitude modulated carrier wave into a trapezoidal wave the slope of the side edges of which correspond in substantially linear proportion to the amplitude of the corresponding undulations, translating the trapezoidal wave into rectangular pulses which vary in width according to the slope of the corresponding side edges of the trapezoidal wave, and translating said rectangular pulses each into at least one narrow width impulse corresponding in displacement to an edge of a rectangular pulse.

2. The method defined in claim 1 wherein the first-mentioned translating operation includes limit clipping the carrier wave between two limits where the sides of the undulations of the carrier wave vary in slope in substantially linear proportion to the amplitude variation of the corresponding undulations.

3. The method defined in claim 1 wherein the first-mentioned translating operation includes clipping the wave at two limits selected near the axis of the wave.

4. The method defined in claim 1 wherein the first-mentioned translating operation includes clipping the wave at two limits selected at opposite sides of the axis of the wave.

5. The method defined in claim 1 wherein the second-mentioned translating means includes differentiating the trapezoidal wave thereby producing a rectangular pulse for each of the leading and trailing edges of each cycle of the trapezoidal wave.

6. The method defined in claim 1 wherein the second-mentioned translating means includes differentiating the trapezoidal wave thereby producing a rectangular pulse for each of the leading and trailing edges of each cycle of the trapezoidal wave and limit clipping the rectangular pulses to reduce the rectangular pulses to substantially the same amplitude.

7. The method defined in claim 1 wherein the

third-mentioned translating operation includes differentiating the rectangular pulses thereby producing a pair of positive and negative impulses from each of said rectangular pulses, one impulse of each pair corresponding to the leading edge and the other to the trailing edge of a rectangular pulse.

8. A method of translating an amplitude modulated carrier wave into an equivalent train of time modulated impulses comprising translating the undulations of the amplitude modulated carrier into a trapezoidal wave the slope of the side edges of which correspond in substantially linear proportion to the amplitude of the corresponding undulations, differentiating the trapezoidal wave to produce a rectangular pulse for each of the leading and trailing edges of each cycle of the trapezoidal wave, differentiating the rectangular pulses to produce a pair of positive and negative impulses from each of said rectangular pulses, one of the impulses of each pair corresponding to the leading edge and the other to the trailing edge of a rectangular pulse, and limit clipping the impulses to produce a train of unidirectional impulses the time displacement of which corresponds with the amplitude variations of the undulations of said carrier wave.

9. A system for translating an amplitude modulated carrier wave into an equivalent train of time modulated impulses comprising means to translate the undulations of said carrier wave into a trapezoidal wave the slope of the side edges of which correspond in substantially linear proportions to the amplitude of the corresponding undulations, means to translate the trapezoidal wave into rectangular pulses which vary in width according to the slope of the corresponding edge of the trapezoidal wave, and means to translate each of said rectangular pulses into at least one narrow width impulse corresponding in displacement with one of the edges of a rectangular pulse, the time displacement of such impulses thereby corresponding substantially to the amplitude of the corresponding undulation of said carrier wave.

10. The system defined in claim 9 wherein the first-mentioned means includes a gate clipper arranged to limit clip the wave between two selected limits.

11. The system defined in claim 9 wherein the second-mentioned translating means includes means for differentiating the trapezoidal wave to produce a rectangular pulse for each of the leading and trailing edges of each cycle of the trapezoidal wave and means to limit clip the rectangular pulses to reduce them to substantially the same amplitude.

12. A system for translating an amplitude modulated carrier wave into an equivalent train of time modulated impulses comprising means to limit clip said carrier wave between two limits where the sides of the undulations of the carrier wave vary in slope in substantially linear proportion to the amplitude variations of the corresponding undulations, means to differentiate said trapezoidal wave to produce a rectangular pulse for each of the leading and trailing edges of each cycle of said trapezoidal wave, means to limit clip said pulses, means to differentiate said pulses to produce a pair of positive and negative impulses from each of said rectangular pulses, one of the impulses of each pair corresponding to the leading edge and the other to the trailing edge of a rectangular pulse, the time displacement between the impulses of each pair corresponding

substantially to the amplitude of corresponding undulations of said carrier wave.

13. A radio receiver having means to detect amplitude modulated carrier waves, means to translate said carrier waves into equivalent trains of time modulated impulses, and means for demodulating the time modulated impulses.

14. The receiver defined in claim 13 wherein the translation means include means to limit clip said carrier wave between two limits where the 10 sides of the undulations of the carrier wave vary in slope in substantially linear proportion to the amplitude variations of the corresponding undulations, means to differentiate the output wave of said limit clipping means to produce rectangular pulses the widths of which correspond substantially to the amplitude of corresponding undulations of said wave, means to limit clip the 15 rectangular pulses to limit them to substantially

the same amplitude, and means to differentiate the rectangular pulses to produce for each of said rectangular pulses at least one narrow width impulse corresponding in displacement to an edge of the rectangular pulse, the displacement of such impulses thereby corresponding substantially to the amplitude of the corresponding undulations of said carrier wave.
